(57) **CLAIM**

The ornamental design for an imaging device, as shown and described.

DESCRIPTION

FIG. 1 is a front, left, and top perspective view of an imaging device embodying the new design;

FIG. 2 is a back, left, and top perspective view thereof;

FIG. 3 is a rear elevational view thereof;

FIG. 4 is a front elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a front, left, and top perspective view of a second embodiment for an imaging device thereof, shown in FIGS. 1-8, having a window cover in an open in use position; and, FIG. 10 is a left side view thereof.

The broken lines in the figures are shown for the purpose of illustrating portions of the imaging device, optional accessories, and/or environmental matter and form no part of the claimed design.
